Primary Examiner — Patricia Palasik

(57) **CLAIM**

The ornamental design for a fully automatic self adjusting hand rollor, as shown and described.

DESCRIPTION

FIG. 1 is a front view of a fully automatic self-adjusting hand rollor.

FIG. 2 is a back view of a fully automatic self-adjusting hand rollor.

FIG. 3 is a right side elevational view of a fully automatic self-adjusting hand rollor.

FIG. 4 is a left side elevational view of a fully automatic self-adjusting hand rollor.

FIG. 5 is a top plan view of a fully automatic self-adjusting hand rollor, and,

FIG. 6 is a bottom plan view of a fully automatic self-adjusting hand rollor.

1 Claim, 6 Drawing Sheets
